WALTER L. YOUNG, OF NEWPORT, CALIFORNIA.

UNDERREAMING-BIT.

1,207,119.

Specification of Letters Patent.

Patented Dec. 5, 1916.

Application filed January 16, 1915. Serial No. 2,756.

To all whom it may concern:

Be it known that I, WALTER L. YOUNG, a citizen of the United States, residing at Newport, in the county of Orange and State 5 of California, have invented a new and useful Underreaming-Bit, of which the following is a specification.

This invention relates to that class of well drilling tools known as the churn drilling 10 type in which the rotating tool reciprocates vertically in the oil or other well to enlarge the hole below the casing.

The primary object of this invention is to provide an improved tool which will combine 15 an under-reamer and drilling bit and to produce a tool of this character which shall be of extremely simple and durable construction, composed of few parts, and which shall be cheap to manufacture and 20 safe, positive and efficient in operation.

More specifically the invention comprises a tool having a lower segmental or substantially semi-circular cutting edge conforming to the circular wall of the hole below the 25 casing, and simple but effective means to maintain said cutting edge in operative relation against said wall below the well casing, said means being embodied in the form of a shifter or relatively free plunger-member 30 lying within the body of the tool during the descent through the casing, and which is adapted to be forced upwardly aslant to project beyond the outer periphery of the body upon the opposite side from the cutting 35 edge after said tool has passed below the casing, thus crowding said cutting edge beyond the produced circular plane of the casing.

The accompanying drawings illustrate 40 the invention.

Figure 1 is a fragmental elevation partly in section on line x^1 , Figs. 6 and 8 showing the newly invented underreaming bit in position below the casing at the bottom of a 45 hole. The shifter is shown latched in the shifting position to which it is forced by inertia of the liquid or plastic contents of the lower portion of the hole as the tool approaches the bottom. Dotted lines show the 50 position of the shifter in the tool during the descent of the tool before entering the water and mud, not shown. Fig. 2 is an elevation from the right of the tool shown in

Fig. 1, the parts being shown intact up to the tool joint. Fig. 3 is an elevation showing the tool in solid and broken lines near the bottom of the hole. Solid lines show the tool as it is being withdrawn; the shifter being in contact with the bottom of the casing so that as the tool ascends farther toward 55 the dotted position the shifter will be held by the casing until it is retracted into the bore of the tool, thus allowing the tool to pass up through the casing as indicated by the dotted lines. Fig. 4 is a top view of the 60 shifter detached. Fig. 5 is a side elevation of the shifter detached. Fig. 6 is a plan section on line x^6 , Figs. 1 and 2 looking up. Fig. 7 is a plan section on line x^7-x^8 , Figs. 1, 2 and 3, looking up. Fig. 8 is a plan section 65 on line x^7-x^8 , Figs. 1, 2 and 3, looking down. Fig. 9 is a cross section of the shifter on line x^9 , Figs. 1 and 5, looking down.

The small arrows on the lines of section indicate the direction of sight and the large 75 arrow on the shank of the tool in Fig. 3 indicates the direction in which the tool is moving to reach the position shown in dotted lines.

In the embodiment shown the body 1 of 80 the tool is provided at its upper end with the usual neck 2 and coupling pin 3 for connection to a sucker rod 4 and at its lower end with a segmental cutting edge 5 of any preferred style. A longitudinal wedge-shaped 85 chamber 6 opens out upon the periphery of the body 1 upon the side opposite the cutting edge 5, and a shifter in the form of a relatively free plunger-member 7 is positioned in said chamber and guided in an aslant direction relative to the axis of the tool when moved up and down therein. The aslant 90 guiding means for said shifter in the present instance consists of the diagonal slide-face 8 of the chamber, the arrangement of which 95 face is such that when the shifter 7 is at the top of the chamber, it projects considerably beyond the outer periphery of the body 1 while when the shifter is at the bottom of said chamber it is positioned entirely within 100 the body. This slide face 8 in the instance shown is formed by a bore extending diagonally into the body 1 from the bottom and this bore together with an axial slot 9, affording communication therefrom to the periphery of the body at the side thereof to 105

ward which the upward slant of the bore approaches, constitutes the open chamber 6. The sides 10 of said axial slot are upwardly tapering due to the aslant arrangement of 5 the bore which cuts through to the periphery of the body at the top thereof and terminates in a socket 11 forming an upper stop for the shifter, said cut through portion forming the upper termination of the slot 9 10 which slot thus extends throughout the entire length of the bore, see Fig. 1. A cross bar 11 bridges the bore 8 at the bottom thereof, its ends being secured in the tool at each side of the bore, said bar forming a 15 lower stop for the shifter and serving to support the shifter against dropping out and also serving to break up and mix the formation drilled by the cutting edge 5 when the tool is reciprocated.

20 During the operation of the tool in the well the shifter 7 is adapted to be normally positioned in the upper end of the chamber 6 as hereinafter described, said shifter in this position extending out beyond the periphery of the body 1 to contact with the wall of the well-hole for the purpose of holding the tool away from said wall at that side thereof and substantially in central alignment with the hole, thereby to maintain 25 the opposite cutting edge outside of the produced plane of the casing and in operative position during continued reciprocation of the tool. Said shifter or plunger member may be wedged or frictionally held in the upper end of the bore if desired or suitable latch means may be provided to yieldingly support the same. In the instance shown a spring pressed latching pin 12 is adapted to project aslant downwardly through the face 30 8 of the chamber 6 and into the path of the shifter 7, said pin terminating at its projecting end in a rounding nose 13. A shoulder 14 of the pin 12 is arranged to seat upon a corresponding seat 15 in the pin bore 16 to limit the movement of the pin into the chamber and a compression spring 17 is interposed between said shoulder and a retaining plug 18, said spring yieldingly holding the pin in its latching position with the nose 13 beneath said shifter to support the same in the normal working position and permitting the pin to be retracted by the shifter only when sufficient force is applied to overcome the spring. Said shifter may 35 be variously constructed and in the present instance comprises a light hollow cylindrical member 19 constructed in the form of a shell of steel or other brittle metal, said shell being open at the bottom and terminating at the top in a rounding portion 20 conforming to the socket 11 of the bore 8. Attached to this cylindrical member 19 is a shoe 21, the inner face 22 of which is concave to fit said member and which face has 40 mounting lugs 23 extending therefrom and arranged to seat in upper and lower openings 24 in the shell-like wall of the member, said shoe being firmly secured in place by pins or keys 25 driven through the cylindrical member at one side of its axis and 70 passing through said lugs.

The shoe 21 is made just sufficiently wide to slide easily in the slot 9 as the cylindrical member 19 to which it is attached is moved up and down in the bore 8 and said shoe is 75 thickened downwardly in order that the outer convex face 26 may lie parallel with the axis of the tool while the inner concave face 22 corresponds to the aslant arrangement of the bore 8, so that when the shifter, comprising the member 19 and shoe 21, is in position in the chamber 6, said outer face 26 is parallel with the wall of the well. This outer face 26 preferably has a convex 80 conformation substantially corresponding to the curvature of the cutting edge 5 and also to the wall of the well which this tool is adapted to drill, say for instance in an 8-inch hole adapted to receive a 6-inch casing, said face is formed by an arc, the radius 90 of which is four inches.

The width of the slot 9 is made less than the diameter of the bore 8 and thus forms aslant shoulders 30 at the intersections of 95 said bore and slot which together with the slide face 8 serves to guide the shifter in its diagonal path.

A lug 27 at the top of the body 1 and upon the same side thereof as the cutting edge 5 and opposite the chamber 6 is provided to hold the tool over in position so that the shoe when in its topmost position will contact with the lower end of the casing 29 as the tool ascends into the casing *a* upon withdrawal from the well. The top face 28 is inclined downwardly and outwardly so that in case the lug strikes said lower casing end 29 as the tool passes into the casing the aslant face will ride over the edge of said end and crowd the tool over to bring the upper end of the shoe 21 fully against the lower end of the casing.

In practical operation when the tool is lowered into the well the shifter will be supported in the chamber 6 and within the body 100 of the tool by the bottom cross bar 11 (see the dotted position of Fig. 3) so that as said tool is lowered through the casing the shifter is out of commission in its retracted position and the cutting edge lies within the circular plane of the casing. After being lowered into operating position below the casing the shifter is brought into commission in its extended position by the combination of inertia of the shifter and the encountering of the same with the plastic material at the bottom of the hole formed of the loosened borings and water (not shown) 115 as the first few strokes of the tool occur upon the beginning of the drilling opera- 120

125 130

tion. This combination just stated forces the shifter upwardly into the socket 11 where it is normally held by the nose 13 of the retaining pin 12 during continued operation of the drill to thus hold the outer convex face 26 in its extended position against the wall of the hole to force the tool body laterally and maintain the cutting edge outside of the produced plane of the 10 casing and in operative position relative to the well.

To withdraw the tool from the well the tool is raised into the casing to bring the shifter into contact with the bottom end 29 of the casing whereupon the shifter is held by said end while the tool continues its ascent (see the solid position of Fig. 3). Immediately after the shifter has contacted with the casing the pin 12, if free to act, is 20 forcibly retracted as it passes the retained shifter upon this continued upward movement of the tool, thus permitting relative movement of the tool and shifter. As the aslant bore 8 moves upwardly the shifter is 25 gradually shifted inwardly of the tool until supported by the cross bar 11, at which time said shifter is fully retracted and entirely within the body of the tool, so that said tool may pass freely up through the casing a.

30 In case the pin 12 becomes fixed from corrosion or other causes the lower edge of the shifter forms a cutter 31 to shear off the projecting end of the pin 12 when the shifter and body relatively move as above described.

During the upward movement of the diagonal slide face 8 upon the shifter the plastic contents which have accumulated in the open chamber 6 below said shifter will 40 tend to be forced out by the relative movement. However, should too great a resistance be offered as the tool is pulled upward, due to clogging of the chamber by rock or the like in the plastic material, the casing 45 end 29 acting upon the top of the shoe 21 will either break the cylindrical shell 19 which is made of comparatively light construction for this purpose, or the mounting lugs 23 of said shoe that are fastened in the 50 cylindrical shell will shear away, thus in either case permitting the tool to continue its upward movement through the casing and allowing the broken shifter pieces to drop to the bottom of the well from where 55 they may be removed by a sand pump or the like. The plunger in this latter case may be repaired or a new one substituted therefor after removing the tool from the well, when said tool is again ready for operation.

60 From the foregoing it is thus seen that I have produced a tool of this character provided with extremely simple and effective means operating against the wall of the hole to force the tool body laterally to hold the cutting edge in operative position to drill a

hole of larger diameter than the well casing through which the tool is lowered.

The lower end of the bore may be deflected vertically and made to extend in cylindrical form coaxially of the bit and may 70 be threaded to receive an extra cutting bit not shown located below the underreaming bit which is shown.

I claim:—

1. In a casing, a tool body having a cutting edge and non-resilient wedging means 75 to force the tool body laterally beneath the casing wall.

2. In a casing, a tool body having a cutting edge on one side and non-resilient 80 wedging means on the opposite side to force the tool body laterally beneath the casing wall.

3. In a casing, a vertically rotating tool body forming a cutting edge, and non-resilient 85 wedging means to force the tool body laterally beneath the casing wall to drill a hole of larger diameter than said body, said means operating against the wall of the hole.

4. In a casing, a vertically rotating tool body forming a cutting edge, and a non-resilient shifter wedge to force the tool body laterally beneath the casing wall to drill a 95 hole of larger diameter than said body, said shifter operating against the wall of the hole.

5. In combination, a vertically rotating tool body having a cutting edge for drilling a hole, and non-resilient wedging means 100 shiftable by the pressure between the tool body and the material loosened by the cutting edge to force said means outward against the wall of the hole.

6. In combination, a vertically rotating tool body having a slide-face that is aslant cutward and upward relative to the axis of the tool body, and a non-resilient shifter wedge sliding along said slide-face and designed to be contained within the path of 110 the tool body when the shifter wedge is at the lower portion of the slide-face and designed to extend beyond said path when the shifter wedge is at the upper portion of said slide-face.

7. In a casing, a vertically rotating tool body having a cutting edge, and horizontally shifting non-resilient wedging means to force the tool body laterally beneath the casing wall to drill a hole of larger diameter 120 than said body, said shifting means operating against the wall of the hole.

8. In a casing, a vertically rotating tool body having a cutting edge, and vertically shifting non-resilient wedging means to 125 force the tool body laterally beneath the casing wall to drill a hole of larger diameter than said body, said shifting means operating against the wall of the hole.

9. In combination, a vertically rotating 130

- tool body having a cutting edge for drilling a hole, and non-resilient wedging means operating against the wall of the hole to force the tool body laterally to drill a hole 5 of larger diameter than said body.
10. In combination, a drill body having a cutting edge, and a non-resilient shifter wedge shiftably mounted on the side of the body opposite said cutting edge.
- 10 11. In combination, a drill body having a cutting edge, and a non-resilient shifter wedge diagonally shifted along said drill body opposite said cutting edge.
- 15 12. In combination, a drill body having a cutting edge, and a non-resilient shifter wedge mounted on the side of the body opposite said cutting edge, said shifter wedge being operated by relative movement between the body and shifter to force the 20 shifter outward beyond the periphery of the tool.
- 25 13. In a well casing, an under-reaming bit reciprocatingly mounted below said casing, said bit comprising a body provided with a segmental cutting edge at the lower end thereof, and a non-resilient shifter wedge to maintain said cutting edge outside of the produced circular plane of said casing.
- 30 14. In a well casing, an under-reaming bit reciprocatingly mounted below said casing, said bit comprising a body provided with a segmental cutting edge at the lower end thereof and non-resilient wedging means adapted to project beyond the outer periphery of the body at the upper end thereof and at that side opposite the cutting edge to thereby force said cutting edge outside of the produced circular plane of said casing.
- 35 15. An under-reaming bit comprising a body having a longitudinally slanting chamber opening out upon the periphery thereof, a cutting edge upon said body at the lower end thereof and opposite said chamber, and a non-resilient wedging member mounted in said chamber and adapted to project beyond the outer periphery of the body to maintain said cutting edge in operative relation.
- 40 16. An under-reaming bit comprising a body having a longitudinal chamber opening out upon the periphery thereof, a non-resilient shifter wedge mounted in said chamber and arranged to project beyond the outer periphery of the body when positioned at the top of said chamber and arranged to lie within said body when positioned at the bottom of said chamber, and a cutting edge at the lower end of said body opposite said chamber.
- 45 17. An under-reaming bit comprising a body having a longitudinal chamber opening out upon the periphery thereof, a non-resilient shifter wedge mounted in said chamber and arranged to move in an aslant direction relative to the axis of said body so that said shifter projects beyond the outer periphery of the body when positioned at the top of said chamber and lies within said body when positioned at the bottom of said chamber, and a cutting edge at the lower end of said body opposite said chamber.
- 50 18. An under-reaming bit comprising a body having a longitudinal chamber opening out upon the periphery thereof, a hollow cylindrical member mounted in said chamber and arranged to move in an aslant direction relative to the axis of said body so that said hollow cylindrical member projects beyond the outer periphery of the body when positioned at the top of said chamber and lies within said body when positioned at the bottom of said chamber, and a cutting edge at the lower end of said body opposite said chamber.
- 55 19. An under-reaming bit comprising a body provided with a cutting edge at the lower end thereof, a bore extending diagonally into said body from the bottom thereof and away from said cutting edge, a slot parallel with said bore and affording communication therefrom to the periphery of the body at that side thereof toward which the diagonal bore approaches, a non-resilient shifter wedge mounted in said bore and adapted to extend through said slot and beyond the outer periphery of the body when positioned at the top of said bore to thereby maintain said cutting edge in operative relation.
- 60 20. An under-reaming bit comprising a body having a longitudinal chamber opening out upon the periphery thereof, a cutting edge upon said body at the lower end thereof and opposite said chamber, a non-resilient shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, and means to support said shifter wedge at the top of said chamber to thereby maintain said cutting edge in operative position.
- 65 21. An under-reaming bit comprising a body having a longitudinal chamber opening out upon the periphery thereof, a cutting edge upon said body at the lower end thereof and opposite said chamber, a non-resilient shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, and yielding means to support said shifter wedge at the top of

said chamber to thereby maintain said cutting edge in operative position.

22. An under-reaming bit comprising a body having a longitudinal chamber opening out upon the periphery thereof, a cutting edge upon said body at the lower end thereof and opposite said chamber, a non-resilient shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, means to support said shifter wedge at the top of said chamber to thereby maintain said cutting edge in operative relation, and a stop at the bottom of said chamber to support said shifter wedge within the body for the purpose set forth.

23. In a well casing, an under-reaming bit reciprocatingly mounted below said casing, said bit comprising a body provided with a segmental cutting edge at the lower end thereof, a non-resilient shifter wedge adapted to project beyond the outer periphery of the body at the upper end thereof and at that side opposite the cutting edge to thereby force said cutting edge outside of the produced plane of said casing, and a lug at the top of said body and upon the same side as said cutting edge, said lug being effective to hold the body over in position so that the shifter wedge when in topmost position will contact with the lower end of the casing as the body ascends into said casing, and thereby move the shifter out of commission to bring said cutting edge inside of the produced plane of the casing.

40 24. An under-reaming bit comprising a body having a longitudinal chamber opening out upon the periphery thereof, a cutting edge upon said body at the lower end thereof and opposite said chamber, non-resilient shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, and a pin projecting into the chamber to support said shifter wedge at the top thereof, the lower edge of said shifter wedge forming a cutter adapted to shear off the projecting end of said pin and thereby permit relative movement of the shifter wedge and chamber.

25. An under-reaming bit comprising a body provided with a cutting edge at the lower end thereof, a bore extending diagonally into said body from the bottom thereof and away from said cutting edge, a slot parallel with said bore and affording communica-

cation therefrom to the periphery of the body at that side thereof toward which the diagonal bore approaches, a hollow cylindrical and non-resilient member slidably mounted in said diagonal bore and provided with a wedge adapted to extend through said slot and beyond the outer periphery of the body when said cylindrical member is positioned at the top of said bore to thereby maintain said cutting edge in operative position.

26. An under-reaming bit comprising a body provided with a cutting edge at the lower end thereof; a bore extending diagonally into said body from the bottom thereof and away from said cutting edge; a slot parallel with said bore and leading therefrom to that side of the perimeter of the body toward which the diagonal bore approaches; a non-resilient hollow cylindrical member slidably mounted in said diagonal bore; a wedge mounted to the cylindrical chamber on the side thereof which faces the slot; said wedge having a substantially flat apex and its outer plane parallel with the axis of said body; and said outer plane of said wedge extending through said slot beyond the perimeter of the body when said cylindrical member is at the top of said bore, thereby maintaining said cutting edge in operative position.

27. In a well casing, a vertically rotating tool body provided with a cutting edge at the lower end thereof for drilling a hole of larger diameter than said tool body; a cylindrical chamber extending diagonally in said body from the bottom thereof and away from said cutting edge; a slot parallel with said chamber and leading therefrom to that side of the perimeter of the body toward which the diagonal chamber approaches; a non-resilient hollow cylindrical member slidably mounted in said diagonal chamber; a wedge mounted to the cylindrical member on the side thereof which faces the slot; said wedge having a substantially flat apex and its outer plane parallel with the axis of aforesaid body; said cylindrical member being adapted to be forced upwardly by the material loosened by said bit during the drilling operation thereof to the upper end of the diagonally slanting cylindrical chamber; said outer plane of said wedge being rounded to conform to the curve of the wall of the hole drilled by said bit; said wedge plane, when said cylindrical member is in its highest position in the cylindrical chamber, extending through said slot and contacting with the wall of the hole drilled by said bit in order to force the tool body laterally and to maintain said cutting edge in operative position.

28. In a well casing, a vertically rotating tool body having a cutting edge for drilling

a hole beneath said casing of larger diameter than said body; a bore extending diagonally into said body from the bottom thereof and away from said cutting edge; a slot parallel with said bore and leading therefrom to that side of the perimeter of the body toward which the diagonal bore approaches; a non-resilient, hollow, cylindrical member slidably mounted in said diagonal bore; a wedge mounted to the cylindrical chamber on the side thereof which faces the slot; said wedge having a substantially flat apex and its outer plane parallel with the axis of said body; and said outer plane of said wedge 15 extending through said slot beyond the perimeter of the body when said cylindrical member is at the top of said bore, thereby bearing against the wall of said hole in order to force the tool body laterally and to 20 maintain said cutting edge in operative position.

29. In a well casing, a vertically rotating tool body having a cutting edge for drilling a hole beneath said casing of larger diameter 25 than the body, a cylindrical chamber extending diagonally in said body from the bottom thereof and away from said cutting edge; a slot parallel with said chamber and leading therefrom to that side of the perimeter of the body toward which the diagonal chamber approaches; a non-resilient, cylindrical member slidably mounted in said chamber and adapted to be forced upwardly in said chamber; yielding means bearing 30 against the lower edge of said member to support the member at the top of said chamber; in said slot, a wedge secured by mounting lugs to the cylindrical member; said wedge having a substantially flat apex and 35 an outer face; said face being convex to conform to the curve of the wall of the hole made by the vertically rotating tool body; said convex face of the wedge being adapted to bear against the wall of said hole, thereby 40 forcing the tool body laterally beneath said casing; and said apex of said wedge being adapted to contact with the lower edge of said casing and thereby either to suppress or to shear said yielding means so 45 that said tool body may be withdrawn through said casing.

30. In a well casing, a vertically rotating tool body having a cutting edge for drilling a hole beneath said casing of larger 50 diameter than the body; a bore extending diagonally into said body from the bottom thereof and away from said cutting edge; a slot parallel with said bore and leading therefrom to that side of the perimeter of the body toward which the bore approaches; a non-resilient, cylindrical shell being slidably mounted in said bore and provided with 55 openings in its wall; in said slot, a wedge having a substantially flat apex, and an inner concave face adapted to fit said cylindri-

cal shell and to be secured thereto; lugs projecting from said concave face being adapted to seat in said openings; means to secure said lugs firmly in said openings; said wedge having an outer convex face adapted to bear 70 against the wall of the hole made by the vertically rotating tool body and thereby to force said tool body laterally beneath said casing; and said lugs being adapted to be shorn away by said cylindrical shell upon 75 the contact of said apex with the lower edge of the casing, when the tool body is withdrawn through said casing.

31. In a casing, a tool body provided with a cutting edge at the lower end thereof; a 80 non-resilient shifter wedge for maintaining said cutting edge outside of and below said casing; and means for forcing said tool body within the casing against the action of said wedge.

32. In a casing, a vertically rotating tool body provided with a cutting edge at the lower end thereof; a non-resilient shifter wedge for maintaining said cutting edge outside of and below said casing; and means 90 at the top of the tool body for forcing said tool body within the casing against the action of said wedge.

33. In a casing, a vertically rotating tool body provided with a cutting edge at the 95 lower end thereof; in said tool body, a cylindrical longitudinal chamber opening upon the perimeter of the tool body in opposite direction to said cutting edge; in said cylindrical chamber a non-resilient cylindrical 100 member slidably mounted and provided with a wedge on its outer side away from said cutting edge; said cylindrical member being adapted to be held at the upper end of said chamber so that said wedge thereby 105 forces and maintains said cutting edge outside of and below said casing; and a projection on the tool body opposite and above said wedge for contacting with the lower edge of the casing upon withdrawal of said 110 tool body through said casing so that the tool body is thereby forced within the casing against the action of said wedge.

34. In a casing, a vertically rotating tool body provided with a cutting edge at the 115 lower end thereof; in said tool body, a cylindrical longitudinal chamber opening upon the perimeter of the tool body in opposite direction to said cutting edge; in said cylindrical chamber, a non-resilient cylindrical 120 member slidably mounted and provided with a wedge on its outer side away from said cutting edge; said cylindrical member being adapted to be held at the upper end of said chamber so that said wedge thereby forces 125 and maintains said cutting edge outside of and below said casing; and said tool body having opposite and above said wedge a projection, the top face of which inclines downwardly and outwardly, so that the projec- 130

tion, when coming in contact with the lower edge of the casing upon withdrawal of said tool body through said casing, may slide over said edge and thereby force said tool body within said casing against the action of said wedge.

5 In testimony whereof, I have hereunto set

my hand, at Los Angeles, California, this 9th day of January, 1915.

WALTER L. YOUNG.
